UNITED STATES PATENT OFFICE.

ELISA E. ROBERTSON, OF NEW YORK, N. Y.

SUSPENDERS.

SPECIFICATION forming part of Letters Patent No. 790,314, dated May 23, 1905.

Application filed July 29, 1903. Serial No. 167,411.

To all whom it may concern:

Be it known that I, ELISA E. ROBERTSON, a citizen of the United States, residing at New York, in the county of New York and 5 State of New York, have invented new and useful Improvements in Suspenders, of which the following is a specification.

This invention relates to suspenders, the primary object of the invention being to provide 10 suspenders for trousers especially adapted for use in warm weather, the same being constructed in such manner as to allow a thorough circulation of air around the shoulders, chest, and back and obviate the binding 15 effect present with suspenders of the ordinary construction.

It is also an object of this invention to construct the suspenders in the main of light porous washable material which may be 20 easily cleaned, the elastic portions of the suspenders being detachable for that purpose; also, to manufacture the suspenders in such a way that they may be worn either over or under the shirt, being therefore especially 25 adapted to the blouse-shirt or shirt-waist at present so popular and fashionable.

With the above general objects in view the invention consists in the novel construction, combination, and arrangement of parts, 30 as hereinafter fully described, illustrated, and claimed.

In the accompanying drawings, Figure 1 is a front elevation of a shirt, showing the suspenders applied thereto beneath the shirt, the suspenders being represented by dotted lines and portions of the suspender-ends in 35 full lines where they project through the slits or openings in the shirt. Fig. 2 is a reverse view of the same. Fig. 3 is a plan view of the body portion or yoke of the suspenders. Fig. 4 is an enlarged front elevation of the 40 suspenders complete.

Like reference-numerals designate corresponding parts in all the figures of the drawings.

The invention resides mainly in what may be termed a "yoke," which is shown in plan in Fig. 3, the same comprising the body portion 1 and the diverging flaps or shoulder-straps 2. The yoke as a whole is formed of 45

strong cellular or open-mesh fabric, so that it may be washed whenever it becomes soiled. When the yoke is in position on the person of the wearer, the body portion extends down and all the way across the back, while the flaps 2 extend over the shoulders and downward over the chest, as indicated in Figs. 1 and 2. By preference the body portion 1 is formed in a separate piece from the front flaps 2 in order that the strands of the fabric may run lengthwise of both the body portion and flaps, thereby giving greater strength to the yoke, the direction of the weave being illustrated in Fig. 3, wherein it will be seen that the front flaps 2 are joined to the body portion 1 by shoulder lap-seams 3. The edge adjacent to the neck of the wearer is provided with a reinforce strip or band 4, while the opposite side edges of the yoke are provided with reinforce-strips 5, which add materially to the strength of the yoke. The lower edge of the body portion 1 is provided with a hem 6, and the extremities of the front flaps are also hemmed, as shown at 7. Two eyelets or metallic buttonholes 8 are secured to the hem 6, while a single eyelet or 75 metallic buttonhole 9 is applied to the hem 7 on each of the front flaps, the said eyelets being adapted to receive the suspender-ends, as shown best in Fig. 4. Each suspender-end in the preferred embodiment of this invention comprises an elastic strap 10, provided at its upper end with a clip 11, having a headed stud 12, adapted to be engaged with and disengaged from the adjacent eyelet or buttonhole piece. The front suspender-ends may also be provided with take-up buckles 13 and snap loops or straps 14, whereby the straps 10 may be disconnected from the terminal straps or suspender-ends 15 for the convenience of the wearer. No 80 special claim to novelty is made for the suspender-ends, however, except that when combined with the yoke they provide for the necessary elasticity or yielding of the suspenders as a whole by reason of the elastic 85 straps 10 referred to. This renders the suspenders as a whole comfortable in use. The portions of the yoke which pass over the shoulders provide a broad bearing for the suspenders, and being thin and porous they 90

render the suspenders cool and comfortable in use. When the yoke or body portion becomes soiled, the suspender-ends containing the elastic straps are detached from the yoke, 5 whereupon the latter may be washed in the ordinary manner.

By providing the shirt (indicated at 16) with slits or openings 17 in the front and back the suspenders may be worn under the 10 shirt and the suspender-ends passed through the slits or openings and connected with the button on the trousers. Preferably the 15 slits or openings 17 are arranged sufficiently low to allow a full effect to the exposed portion of the shirt, the result being that the fullness around the waist will conceal the suspender-ends. If desired, a scarf or other 20 form of belt may be worn around the waist, and the latter will also aid in concealing the suspender-ends. Under the arrangement described the weight of the trousers will be borne by the suspenders and not be thrown upon the hips, which occasions the use of a belt fastened tightly around the waist.

Having thus described the invention, what 25 I claim as new, and desire to secure by Letters Patent, is—

The herein-described suspenders, comprising three sections formed entirely of open-mesh material, one of said sections having 30 converging side edges and an inwardly-curved end edge, the other edge being turned over and secured to form a hem, the other sections being secured to the said first-named section on opposite sides of its inwardly-curved portion, a reinforcing-band secured to the inwardly-curved edge of the said first-named section and to the last-named sections, reinforcing-bands extending along the 35 outer edges of all said sections for their entire lengths, and means carried by each of said sections for securing to a garment. 40

In testimony whereof I affix my signature in presence of two witnesses.

ELISA E. ROBERTSON.
